UNITED STATES PATENT OFFICE.

EMIL R. DRAVER, OF RICHMOND, INDIANA.

VULCANIZING-TOOL.

1,218,245.

Specification of Letters Patent.

Patented Mar. 6, 1917.

Application filed August 5, 1916. Serial No. 113,366.

To all whom it may concern:

Be it known that I, EMIL R. DRAVER, a citizen of the United States, residing at Richmond, in the county of Wayne and 5 State of Indiana, have invented certain new and useful Improvements in Vulcanizing-Tools; and I do hereby declare the following to be a full, clear, and exact description of the invention, such as will enable others 10 skilled in the art to which it appertains to make and use the same.

My invention has for its object to provide an extremely simple, highly efficient and convenient vulcanizer tool or device, 15 by the use of which patches may be conveniently applied at a minimum cost to the inner tubes of pneumatic tires. Generally stated, the invention consists of the novel construction and combination of parts hereinafter described and defined in the claims.

In the accompanying drawings which illustrate the invention, like characters indicate like parts throughout the several views.

25 Referring to the drawings:

Figure 1 is a perspective view showing the improved vulcanizer tool;

Fig. 2 shows the tool partly in side elevation and partly in vertical section;

30 Fig. 3 is a section on the line 3—3 of Fig. 1;

Fig. 4 is a vertical longitudinal section of the tool, some parts being broken away, and showing the same in use to hold a 35 patch and solid combustible element against the inner tube;

Fig. 5 is a plan view of the so-called pan;

Fig. 6 is a section on the line 6—6 of 40 Fig. 5;

Fig. 7 is a plan view of the solid combustible element;

Fig. 8 is a section on the line 8—8 of 45 Fig. 7;

Fig. 9 is a plan view of the patch;

Fig. 10 is a section on the line 10—10 of Fig. 9;

Fig. 11 is a plan view showing a slightly modified form of the solid combustible element; and

50 Fig. 12 is a section on the line 12—12 of Fig. 11, a portion of one jaw of the vulcanizer tool being shown in dotted lines.

The tool is in the form of a pair of 55 pliers and is made up of two levers 13 and 14 connected by an intermediate pivot.

This pivot is of novel construction and, as shown, is formed by providing the lever 13 with a cylindrical hinge hub 15 formed with a peripheral gap 16, and by providing the lever 14 with a cylindrical trunnion 17 that works pivotally within the hub 15. This trunnion 17, for lightness, is made tubular, and at its ends, it is formed integral with side flanges of the lever 14, the said side flanges being connected thereto by webs 18 that are of slightly less circumferential dimensions than the gap 16. Furthermore, the said gap 16 and webs 18 are so related to the levers that said webs may be moved laterally through the gap 16 when and only when the levers are in the relative position shown by full lines in Fig. 2.

The lever 13, at its tube engaging end, has a disk-like clamping plate or platen 19. At the corresponding end, the lever 14 is provided with a finger or stud-like presser foot 20 that is approximately in axial alignment with the plate 19. Preferably, also, the lever 13 is formed with perforated lugs 21 that adapt it to be rigidly secured by screws not shown, to a bench or suitable support, when it is desired to use the tool as a local fixture rather than as a portable tool.

80 A coiled spring 22 is interposed between the handle ends of the levers 13 and 14. This spring 22 exerts a force tending to hold the presser foot 20 against the clamping plate or platen 19, and it must be placed in position after the levers 13 and 14 have been properly pivotally connected. When the two levers are in relative position shown by full lines in Fig. 2, they may be made by lateral movement, the one in respect to the other, to be moved into pivotal connection or separated. When they are thus properly connected and the lever 14 is moved into the position indicated by dotted lines in Fig. 2, the spring 22 may be inserted between the handle ends thereof, and the said spring, when thus inserted, and even when compressed solid, will prevent the levers from being moved back to the relative position shown by full lines in Fig. 100 2, and hence, will prevent the said levers from becoming accidentally separated.

105 The inner tube of a tire (Fig. 4), is indicated by the character *a* and in Figs. 4, 9 and 10, a vulcanizing patch is indicated by the character *b*. This patch *b* may be 110 of any suitable or well known commercial

composition adapted for the purpose indicated, and it would preferably be normally covered, either on one or both faces with a thin sheet of oil paper b^1 .

5 In Figs. 4, 7 and 8, the preferred form of solid combustible element is indicated by the character c . This solid combustible element also may be of any suitable or well known composition adapted when lighted, 10 to produce the heat required for the vulcanization of the patch.

In Figs. 4, 5 and 6, the preferred form of pan is shown and is indicated by the numeral 23. This pan, as shown, has an 15 upwardly concave bottom and rounded edges and the bottom of the solid combustible element c is made to fit the bottom of the pan, but is of considerably less diameter than the pan. This pan is preferably of pressed sheet metal and may be used over and over again, so that it is really a part of the vulcanizing tool proper.

In the vulcanizing operation the tube a is placed on the clamping plate or platen 25 19, the patch is placed over the puncture thereof, the pan is placed over the patch and the solid combustible element is placed in the said pan, as clearly shown in Fig. 4. The hand grip ends of the levers 13 and 14 30 then being released, the spring 22 will force the presser foot 20 tightly against the upper surface of the solid combustible element, and the said pan, patch and tube will then be tightly clamped together. The solid combustible element may then be lighted, and in burning, will produce the heat required 35 for vulcanization. As the solid combustible element burns away, the spring 22 will cause the presser foot 20 to follow up, and hence 40 will maintain the proper pressure on the patch during the entire vulcanizing operation, regardless of the burning away of the fuse. This arrangement is preferred because the solid combustible element, as well 45 as the other elements are very firmly pressed to place. However, if desired, the solid combustible element may be provided with a perforation through which the presser foot 20 may project into direct contact with the 50 bottom of the pan. Such a solid combustible element is shown in Figs. 11 and 12, wherein the combustible element is indicated at c^1 , and its axial perforation at c^2 .

The plier or pivoted lever form of the tool 55 is highly desirable because it throws the hand engaged portion to points remote from the tube and gripping portions and prevents the former from being made hot by the burning of the solid combustible element. 60 Hence, the tool may be handled and quickly removed the instant that the vulcanization of the patch is completed. Also, it enables the vulcanizing tool to be very quickly and easily applied in working position.

65 As the pan may be used over and over

again, it is not necessarily supplied with each solid combustible element, and economy in the patching vulcanizing operation is effected. The tool itself may be constructed at small cost. The efficiency of the tool has 70 been demonstrated in practice. The tool, while especially designed for vulcanizing inner tubes of pneumatic tires, may, nevertheless, be generally used for applying vulcanized patches to rubber articles, such as 75 rubber coats, rubber boots, and the like.

What I claim is:

1. A vulcanizing device comprising a pair of coöperating clamping members, one thereof having a pan-like clamping abutment and the other having a coöperating finger-like presser foot alined with the central portion of said coöperating clamping abutment, the latter having marginal portions that project far beyond the coöperating end of said presser foot, and spring means yieldingly pressing the said clamping members, the one toward the other. 80

2. A vulcanizing device comprising a pair of pivotally connected levers, one of said levers having a pan-like clamping abutment and the other having a coöperating rigidly secured finger presser foot alined with the central portion of said coöperating clamping abutment, and spring means applied to said levers for yieldingly pressing said presser foot toward said clamping abutment. 90

3. A vulcanizing device comprising a pair of pivotally connected levers, one of said levers having a pan-like clamping abutment and the other having a coöperating rigidly secured finger-like presser foot alined with the central portion of the said coöperating clamping abutment, and a spring compressed 100 between the handle ends of said levers. 105

4. A vulcanizing device comprising a pair of pivotally connected levers, one of said levers having a pan-like clamping abutment and the other having a coöperating rigidly secured finger-like presser foot alined with the central portion of the said coöperating clamping abutment and three individual separable elements, to-wit, a pan, a vulcanizing patch and a solid combustible element temporarily held together by the said abutment and presser foot, with the said vulcanizing patch opposed to said abutment and said combustible element opposed to said presser foot, and with the said presser foot exerting its compressing force on the 110 central portion of said pan. 115

5. A vulcanizing device comprising a pair of pivotally connected levers, one of said levers having a pan-like clamping abutment and the other having a coöperating rigidly 125 secured finger-like presser foot alined with the central portion of the said coöperating clamping abutment and three individual separable elements to-wit, a pan, a vulcanizing patch and a solid combustible element 130

temporarily held together by the said abutment and presser foot, with the said vulcanizing patch opposed to said abutment and said combustible element opposed to 5 said presser foot, and with the said presser foot exerting its compressing force on the central portion of said pan, and the said pan having an inwardly bulged bottom and outwardly flaring rim, said rim projecting beyond the margin of said combustible element.

6. A vulcanizing tool comprising a pair of levers having opposing clamping devices at one end, one of said levers having a cylindrical hinge hub with a peripheral gap 15 and the other of said levers having a trun-

nion connected thereto by a web insertible through said gap to permit said trunnion to be pivotally seated in said hub, when the handle ends of said levers are forced together, and a spring interposed between the handle ends of said levers, and when in position, presenting the said levers to be moved to a position in which they may be separated at their pivotal connection.
